UNITED STATES PATENT OFFICE.

GUY R. FOX, OF EVANSTON, ILLINOIS.

PLASTERING-MACHINE.

1,017,256.

Specification of Letters Patent. Patented Feb. 13, 1912.

Application filed February 21, 1911. Serial No. 610,095.

To all whom it may concern:

Be it known that I, Guy R. Fox, a citizen of the United States, residing at Evanston, in the county of Cook and State of Illinois, have invented a new and useful Plastering-Machine; and I do hereby declare the following to be a full, clear, and exact description of the invention, such as will enable others skilled in the art to which it appertains to make and use the same.

This invention relates to a new and useful machine, adapted for plastering walls and the like.

The invention in its broadest scope aims at its primary object to provide a vertically moving platform, including means for holding the same in raised positions.

As another object, the invention aims to provide means for mixing the plaster.

A further object of the invention is to provide a funnel shaped member having arranged therein a vertical spiral feed, for feeding the plaster through the funnel to the revoluble trowel or helico-volute plastering knife.

Another object of the invention is to provide a mixing tank (which is supported in annular bands) having the mixing mechanism therein, which mixing mechanism and spiral feed are geared to the same shaft so the two will operate simultaneously.

A further feature of the invention is to provide a flexible connection between the mixing tank and the funnel, so that as the plaster is properly mixed, it will pass automatically into the funnel, where it is elevated by the spiral feed.

The object of rendering the platform vertically movable is to raise the funnel, the helico-volute plastering knife (which is rotated by the spiral feed) and the spiral feed, so that the knife will be brought adjacent the ceiling of a room, or to the proper position adjacent the upper portion of the side wall, whereby the knife may perform its intended functions. When the platform is raised, the mixing tank is also raised, so that the mixing tank and the funnel shaped member will remain in their proper relative positions.

In the present invention there are two mixing tanks and two funnel shaped members, each having a spiral feed and plastering knife, one funnel shaped member being arranged at right angles to the other.

A further object of the invention is to provide a foldable or collapsible frame, for the support of the vertically movable platform, said frame being provided with caster wheels of the design shown in the drawings, so that the apparatus may be moved from place to place. In the drawings, however, there is disclosed a certain form and construction of apparatus, but, in practical fields, this form and construction may require alterations, to which the applicant is entitled, provided the alterations are comprehended by the appended claims.

The invention comprises further features and combinations of parts hereinafter set forth, shown in the drawings and claimed.

In the drawings:—Fig. 1 is a view in side elevation of the plastering apparatus constructed in compliance with the invention. Fig. 2 is a plan view of the apparatus, showing the relative positions of the various parts. Fig. 3 is a view in elevation and partly in section of the frame, for supporting the vertically movable platform. Fig. 4 is a view in elevation of the frame, showing the same collapsed or folded. Fig. 5 is a sectional view through the mixing tank, in order to disclose the interior features thereof. Fig. 6 is a sectional view through one of the funnel shaped members or plaster holding casings, clearly disclosing the spiral feed mechanism therein and the helico-volute plastering knife. Fig. 7 is a detail view of the plastering knife. Fig. 8 is a detail view of a portion of the apparatus. Fig. 9 is a plan view of the platform 17, showing how it engages the rods 5, by virtue of the recesses 18.

Referring more specifically to the accompanying drawings, 1 designates the frame as a whole, which is constructed of tubular rods 2, which are connected together by the unions 3. This frame is foldable or collapsible, as shown in Fig. 4. Receivable within the lower ends of the lower sections of the sectional vertical rods 5 at the corners of the frame are threaded the shanks 6 of the plates which are provided with semi-circular slots 4^a. Castings 7 are provided, in which the caster wheels 8 are journaled. These castings are arranged below the plates 4 and movably adjacent thereto, as shown in Fig. 8. Extending through the semi circular slots 4^a and the plates 9 (which are integral with the castings 7) are the bolts 10, by

which the plates 4 and 9 may be held in proper relations with one another. As before stated the rods 5 are made in sections, which are connected together by the unions 3, 11, and 12, into which unions 11 and 12, the sections of the tubular rods 13 and 14 are threaded. The sections of each of the tubular rods 13 and 14 are joined by the turn buckles 15. By virtue of the turn buckle, rigidity and strength are afforded for the frame, so as to hold the platform 17 properly in position. This platform at its corners is recessed, as shown at 18, to receive the vertical posts or tubular rods 5, thus affording means whereby the platform may be guided as the same is raised or lowered.

To raise and lower the platform, cables or the like 18^a are fastened thereto and passed over pulleys 19, which are suspended by the hooks 20 from the upper extremities of the tubular members or posts 5. These hooks 20 engage the upper hollow portions of the said tubular posts 5. The cables 18, after passing over the pulleys 19, are wrapped several times about the plates or members 21, thus affording means for holding the platform in its raised or lowered position.

To permit the frame of the apparatus to collapse, the unions 11 and 12 are provided with lateral extensions 5^a, to which the rods or bars 14 are pivoted, as at 5^b. To hold the frame rigid, however, the lateral extensions 5^a, and the rods or bars 14 are provided with registering apertures, through which the split or dowel pins 5^b are extended. By virtue of these dowel pins, the frame is held rigidly erected.

To collapse the frame of the apparatus as shown in Fig. 4, the dowel pins 5^b are first removed, and because of the rods 2 and 14, being pivoted at 3^a and 5^b, the longitudinal sides of the frame may be brought together as shown in Fig. 4, after which the tongues 59 may be disconnected by removing their pivot bolts, thus rendering it possible to pack the frame in a small compass. The dowel pins 5^b pass through the lateral extensions 5^a and through the apertures 5^a of one of the sections of the rods 14, as shown in Fig. 3. After having removed the dowel pins 5^b to collapse the frame as shown in Fig. 4, the pins are re-inserted in the extensions 5^a, so as to prevent their loss. The frame not only may be collapsed as shown in Fig. 4, but may be knocked down or disjoined, by disconnecting the unions 11 and 12, and 3, the pivots 5^b and 3^a, the dowel pin connections 5^b, and the turn buckles 15, as well as the tongues 59, after which the various parts of the frame may be packed in one pile.

The vertically movable platform is designed for the purpose of carrying and supporting the various parts of the helico volatile plastering machine, namely, the mixing

apparatus, the funnel shaped members and their spiral feed mechanisms and plastering knives, and a conventional form of engine or motor, for furnishing power to the driving crank shaft. The engine or motor 70 is only illustrated in outline, and is designed to represent a conventional form of motor. This motor 22 is supported immediately upon the platform, and is provided with connections 24 to the crankshaft 75 25. However, the mixing tanks 26 are supported by the standards 29. These standards 29 are hollow and their lower ends are threaded into sockets 30 of the platform. Received by the upper portions of the 80 standards are the shanks 31 of the posts 32. These posts 32 are provided with enlargements 33, thus affording bearings 34 for the crank shaft 25. Secured by straps *h* to the posts 32 are the annular bands 41, in which 85 the mixing tanks 26 are supported and arranged.

One end of the crank shaft 25 is mounted in a bearing 32^b, the shank 31^b of which is received in the standard or support 29^a, 90 which is threaded into the socket 30^a. The funnel shaped members, or plaster holders, or plaster holding casings 27 and 28 are supported by the standards *a*, through which the thumb screws *b* extend. These 95 thumb screws *b* engage the annular rings *c*, which extend through the ears *e* of the funnel shaped members. The rings *c* are split or severed, and connecting their adjacent ends are turn buckles *d*, by which the rings. 100 may be drawn tightly about the funnel shaped members. By the construction of the thumb screws and rings, the funnel shaped members may slightly move on pivots.

The mixing tanks are provided with closure members 38^b, which close the openings at one end of the tanks, as shown in Fig. 5, there being guides 38^a for the said closure members. At one end of the crank shaft 110 25, a gear wheel 35 is arranged, which meshes with the gear wheels 36 of the combined feed and mixing screws 38. When the gear wheels 36 are rotated, the combined feed and mixing screws 38 are rotated with them, that is, when the conventional form of clutch mechanisms 37 are operated, as will be clearly understood from Fig. 5. By the combined mixing and feeding or conveying screws, the plaster is fed from the mixing tanks, through the flexible connections 39 into the funnel shaped members or plaster holding casings 27 and 28. The connections 39 are supported relatively 115 with regard to the tanks by the chains 40. 120 The funnel shaped member or plaster holding casing 28 is steadied by the chains *h*, which connect to the posts *g*. Arranged in the funnel shaped members or plaster holding casings are the spiral feed screws 42, which 125

130

are provided with hollow shafts 44. The lower end of the vertical shaft 44 is formed with a restricted portion, which is seated in a socket 48. Secured to the vertical shaft 44 is a worm wheel 45, which meshes with the worm 46 of the shaft 25. The horizontal shaft 44 is also provided with a restricted portion (not shown), which is seated within the bearing 32^a, the shank of which is received in the hollow standard 29^b. Rotatably carried by the horizontal shaft 44 (which is hollow) is a gear wheel 46^a, which meshes with the gear wheel 45^a of the shaft 25. Thus it will be seen that by the worm wheel and worm connection and the gear connections 46^a and 45^a, the vertical and horizontal shafts 44 may be rotated. Arranged in the hollow shafts 44 are the shafts 56 of the plastering knives 54. These shafts 56 are formed with elongated recesses 52, into which the thumb screws 51 extend, thus causing the shafts 56 and 44 to rotate as one body.

By virtue of the recess 52 being elongated, the shafts 56 may have vertical movement. The ends of the shafts 56 are provided with thrust bearings, in the plates 49, which are arranged above the springs 50. The springs 50 are seated in the ends of the hollow shafts 44, thus constituting yielding means for the shafts 56. Surrounding the feed screws 42 are the cylinders 53, through which the plaster is elevated to the top and the outer portions of the funnel shaped members. As the plaster leaves the cylinders 53, it is picked up by the revoluble spiral or snail shaped or helico-volute plastering knives 54 and plastered upon the ceiling or side wall. The plastering knives 54 are made of resilient metal, and the spiral portions of the knives as shown in Fig. 7 are slightly spaced apart, so that when the knives are held yieldably against the wall, the said spiral portions of the knife will telescope one another. The plastering knives are rotated with the shafts 44, by virtue of the thumb screw and recess connection 51 and 52. By virtue of the springs 50, the helico-volute plastering knives 54 are allowed a yielding action as they are revolving, in order to properly and evenly plaster the ceiling or side wall.

The sides of the frame of the apparatus are provided with tongues 59, the extremities of which have handles 60. By the handles 60 and the tongues 59, the plastering machine or apparatus may be moved from place to place, so that the entire ceiling or side wall may be completely plastered. The ingredients of the plastering material are emptied into the mixing tanks, by way of the hoppers 63.

After the tanks are sufficiently filled, the combined feed and mixing screws are rotated by virtue of the gear connections 33

and 36, between the screws and the shaft 25, until the plastering mixture is thoroughly agitated. As the material is agitated and thoroughly mixed, it is fed forward through the tanks and the flexible connections 39 70 into the lower portion of the funnel shaped member 27 and one end of the funnel shaped member 28. The material is then fed upwardly and outwardly of the cylinders 53, until it is picked up by the plastering knives and plastered upon the ceiling or side wall. These plastering knives are in the form of the contour of a snail, or may be termed helico-volute knives, thus constituting efficient means for thinly coating the ceiling and side wall. These knives are constructed from a piece of resilient material, the volute scrolls of the knives are substantially flat, the scrolls diminish in width toward one end, with the diminished end connected to the shaft 56. As shown in Fig. 6 of the drawings the funnel shape member 27 is provided with a portion 27^a, by which the waste plaster may be carried back to the spiral feed of the cylinder 53.

From the foregoing, taken in connection with the annexed drawing, it will be observed that a novel form of plastering machine has been devised for automatically plastering ceilings and side walls of rooms 95 and the like, and one which is found to be practicable and essentially useful by plasterers.

The invention having been set forth, what is claimed as new and useful is:—

1. In a plastering machine, a funnel shaped member, a cylinder therein, a spiral feed mechanism arranged in the cylinder and having a hollow shaft, a revoluble knife above the funnel shaped member and having a shaft arranged telescopically within the hollow shaft of the feed mechanism, and means for yieldably mounting the shaft of the knife.

2. In a plastering machine, a funnel shaped member, a spiral feed mechanism therein having a hollow shaft, a revoluble plastering knife above the funnel shaped member and provided with a shaft extending into the shaft of the feed mechanism, means for yieldably mounting the shaft of the plastering knife, and connections between the two shafts to permit them to rotate as one body.

3. In a plastering machine, a vertically movable platform, supports thereon having thumb screws penetrating their ends, an annular member having a turn buckle engaged by the thumb screws, and a funnel shaped member including a revoluble plastering 125 knife and plaster feed mechanism, said funnel shaped member being supported within the annular member.

4. In a plastering machine, a funnel shaped member including a revoluble plas-

1. In a plastering machine, a funnel shaped member, a plaster mixing tank having a flexible connection with the funnel shaped member, said tanks having mixed mechanism a revolute 50
5 crank shaft having gear connections with the feeding mechanism, and knife, and with the mixing mechanism, for transmitting motion thereto.
2. In a plastering machine, a funnel shaped member including a revolute plastering knife and plaster feed mechanism, a plaster mixing tank having a flexible connection with the funnel shaped member, said tank having mixing mechanism, a revolute 55
10 crank shaft having gear connections with the feeding mechanism, and knife and with the mixing mechanism, for transmitting motion thereto, and means for throwing the mixing mechanism in and out of gear.
3. In a plastering machine, a funnel shaped member, a revolute spiral feed mechanism therein including two telescopically arranged shafts, the outer one of which carrying a spiral feed, while the inner one is 60
15 provided with a spiral shaped plastering knife one end of which is disposed beneath the termination of the spiral feed.
4. In a plastering machine, a funnel shaped member, a revolute spiral feed mechanism therein including two telescopically arranged shafts, the outer one of which carrying a spiral feed, while the inner one is 65
20 provided with a spiral shaped plastering knife one end of which is disposed beneath the termination of the spiral feed, and means for causing the two shafts to rotate as one body.
5. In a plastering machine, a funnel shaped member, a spiral feed mechanism therein, 70
25 and a yieldably mounted snail shaped plastering knife cooperating therewith.
6. In a plastering machine, a revolute spiral feed mechanism including a yieldably mounted spiral shaped plastering knife rotatable therewith, and a funnel member disposed below the plastering knife and surrounding the spiral feed mechanism, said funnel member having means to convey the waste plaster back to the feed mechanism.
7. In a plastering machine, a funnel shaped member, a revolute feed mechanism therein, a knife revolute with the feed mechanism extended slightly beyond the member, said knife being yieldably mounted and coiling and tapering toward the termination of the feed mechanism.
8. In a plastering machine, a feed mechanism, a surrounding member therefor, a resilient plastering knife, coiling and tapering 80
30 toward its center revolute with the feed mechanism, and adapted to be fed thereby, each coil being lower than the preceding one until the feed mechanism is reached.
9. In a plastering machine, a revolute spiral feed mechanism, merging into a spiral 85
35 shaped resilient plastering knife, and a surrounding plaster holder for the feed.
10. In a plastering machine, a revolute spiral feed mechanism, merging into a spiral shaped resilient plastering knife, a surrounding plaster holder for the feed, said knife being yieldably mounted with relation to the feed mechanism, and means for causing the knife to rotate with the feed mechanism.
11. In a plastering machine, a spiral feed mechanism having a hollow shaft, a revolute 90
40 plastering knife provided with a shaft extending into the hollow shaft and yieldably mounted therein, means to cause the two shafts to rotate as one body, a surrounding inclosure for the spiral feed mechanism, a mixing tank communicatively connected to the surrounding inclosure, a mixing mechanism in the tank, and means for operating the mixing mechanism and the hollow shaft.
12. In a plastering machine, a single helico-volute resilient plastering knife, the scrolls of which being substantially flat.
13. In a plastering machine, a single helico-volute compression knife, the scrolls of which being substantially flat and means for revolving the knife.
14. In a plastering machine, a spiral resilient revolute plastering helico-volute knife, the volute scrolls of which being substantially flat, the knife being attached at one end and free at the other, a plaster mixing mechanism, and means for operating the mixing mechanism and revolving the knife simultaneously.
15. In a plastering machine, a helico-volute resilient revolute yieldably mounted plastering knife, the volute scrolls of which being substantially flat, the knife being attached at one end and free at the other.
16. In a plastering machine, a helico-volute resilient revolute yieldably mounted plastering knife, the volute scrolls of which being substantially flat and diminishing in width toward one end of the knife, and a spiral feed mechanism for the knife.
17. In a plastering machine, a helico-volute resilient revolute plastering knife, the volute scrolls of which being substantially flat, the knife being attached at one end and free at the other, a plaster mixing mechanism, and means for operating the mixing mechanism and revolving the knife simultaneously.
18. In a plastering machine, a helico-volute resilient revolute yieldably mounted plastering knife, the volute scrolls of which being substantially flat, the knife being attached at one end and free at the other.
19. In a plastering machine, a helico-volute resilient revolute yieldably mounted plastering knife, the volute scrolls of which being substantially flat, the knife being attached at one end and free at the other, and means for revolving the knife.
20. In a plastering machine, a helico-volute resilient revolute plastering knife, the volute scrolls of which being substantially flat, and diminishing in width toward one end of the knife, and a spiral feed mechanism for the knife.
21. In a plastering machine, a helico-volute resilient revolute plastering knife, the volute scrolls of which being substantially flat, and diminishing in width toward one end of the knife, a spiral feed mechanism for the knife, and means for simultaneously operating the feed mechanism and the knife.
22. In a plastering machine, a helico-volute resilient revolute spiral yieldably mounted plastering knife, the volute scrolls of which being substantially flat, and diminishing in width toward one end of the knife, feed mechanism for the knife, a plaster-mixing mechanism for the knife, a

mechanism, and means for simultaneously operating the mixing mechanism, feed mechanism and the knife.

23. In a plastering machine, a helico-volute revoluble plastering knife, the volute scrolls of which being substantially flat, and diminishing in width toward one end of the knife, and a feed mechanism for feeding the smaller end of the knife.

10 24. In a plastering machine, a revoluble helico-volute plastering knife, the volute scrolls of which being substantially flat, and diminishing in width toward one end of the knife, and a plaster holder arranged below the knife.

15 25. In a plastering machine, a helico-volute plaster knife constructed from a piece of resilient material, the volute scrolls of the knife being substantially flat.

20 26. In a plastering machine having a revoluble member, a helico-volute plaster knife constructed from a piece of resilient material, the volute scrolls of the knife being substantially flat, the scrolls diminishing in width toward one end, with the diminished end connected to the revoluble member of the machine.

25 27. In a plastering machine having a revoluble member, a helico-volute plaster knife

constructed from a piece of resilient material, the volute scrolls of the knife being substantially flat, the scrolls diminishing in width toward one end, with the diminished end connected to the revoluble member of the machine, a feed mechanism for feeding the diminished end of the knife and a plaster holder surrounding the feed mechanism, the holder having a portion inclined toward the feed mechanism for returning the waste plaster back to the feed mechanism.

30 28. In a plastering machine, a revoluble plastering knife, a feed mechanism for feeding one end of the knife, a plaster holder casing surrounding the feed mechanism and arranged below the knife, the casing having a top member inclined inwardly and downwardly toward the center of the casing, and a cylindrical wall surrounding the feed mechanism upon the interior of the casing and connecting the top and the casing.
